COMPRESSION RING

Application filed October 18, 1932. Serial No. 638,293.

My invention relates to compression rings of the type used on pistons and more particularly to the type of ring with which there is used a spring which is placed in the bottom 5 of the piston groove and which operates to yieldingly press the piston ring or compression ring outwardly into yielding engagement with the wall of the cylinder.

The present invention has among its 10 salient objects to provide a compression ring so constructed on its inner edge that it not only has a seat to receive the spring, but has one or more beveled edges for guiding the spring into the seat or recess provided therefor, thus greatly facilitating the assembling 15 of the spring and the ring in place in the piston groove; to provide an improved ring structure with an increased sealing area and therefore an increased cooling surface; to provide an improved ring of the character referred to which can be made in two co-operating parts with a common spring for both parts, each part having a portion of the 20 spring seat formed therein and thus making it possible also to stagger the joints of the ring parts, whereby the joint in each ring part is bridged by the other ring part; and, in general, to provide a simplified, practical and efficient compression ring of the character referred to.

In order to fully illustrate my invention, I have shown the two forms thereof on the accompanying sheet of drawing, which I will now describe.

Figure 1 is an enlarged, fragmentary sectional view through portions of the piston, cylinder wall, and a two part ring in place therein;

Figure 2 is a transverse sectional view 40 through a cylinder and piston, and taken on the lines 2—2, and 2'—2' of Fig. 1; and

Figure 3 is a sectional view similar to that shown in Fig. 1, but showing a one piece ring with spring seat, spring and beveled inner edges.

Referring now in detail to the drawing, 45 4 designates the cylinder wall and 5 the piston and 6 the piston groove, in all views, only one groove being shown and that on an enlarged scale for clearness.

My improved compression ring, as illustrated in Figs. 1 and 2, consists of two parts, 7 and 8, with a spring receiving seat 9 formed in their inner edges, and from the edges of said seat 9, said ring parts are formed with 55 beveled edges, 7' and 8'. The spring is designated 10 and is of the undulating form and is sufficiently resilient to press the ring parts outwardly against the wall 4 of the cylinder.

The object and advantage of providing the 60 beveled inner edges to the ring parts is to facilitate the assembling of the ring parts and the spring in proper relationship within the piston groove. It will be readily understood that when the spring is placed in the 65 groove and the ring parts are then placed therein that these beveled edges will automatically guide and cause the spring to move into the spring-receiving seat 9, as said ring parts are pressed into the groove. The ring 70 parts are also wider along the surfaces which engage with the top and bottom walls of the piston groove, that is, along the surface designated 11 and 12, thus increasing the sealing surface area, and also the cooling surface. 75

By reference to Fig. 2, it will be seen that the joint or split in the ring part 7, is at one place, designated 13, and the joint or split of the other ring part 8, is at 13', the ring part 7 being broken away for a part of the circumference in order to show it. By this arrangement a body part of each ring part bridges the joint or split in the other part and thus an open joint or split across the full axial area of the ring is prevented.

In Fig. 3, I have shown a one piece ring, designated 14, with a spring-receiving seat 15, with the beveled inner edges 14', 14' and a spring 16 of the same form shown in the other views.

It will be understood from the showing in all views that if the undulating spring is placed first in the piston groove, it will naturally seat edgewise upon the bottom or lower floor of the groove. It will also be clear that 95 when the ring is put into place, the lower beveled edge, as it closes in around the groove, will lift the spring and cause it to snap into the seat formed to receive it in the manner clearly indicated in both Figs. 1 and 3.

I do not limit my invention to the showing as made for explanatory purposes, except as I may be limited by the hereto appended claims.

5 I claim:

1. A compression ring of the character referred to having formed in its inner side a spring-receiving seat of rectangular form in cross section and having an inner side beveled

10 inwardly to the inner edge of the bottom horizontal wall of said seat, and a spring of rectangular form in cross section to fit into said seat, said beveled edge operating to guide said spring into said seat as the ring and

15 spring are placed in a piston groove.

2. A compression ring formed in two parts and having formed in their inner edges a common spring-receiving recess of rectangular form in cross section, one of said ring

20 parts having its inner side beveled inwardly to the inner edge of the bottom horizontal wall of said recess, and a spring formed in cross section to fit into said recess.

3. A compression ring formed in two parts

25 and having their inner sides beveled with the beveled surfaces converging toward the joint between said ring parts, then extending outwardly radially and parallel with each other and then axially to form a spring-re-

30 ceiving seat of rectangular form across said joint, and a spring formed to fit said seat and to bridge said joint, said beveled sides being adapted to guide said spring into operating position as said parts and spring are assembled together.

35 4. In combination with a piston having a ring groove therein, a compression ring in two parts having formed in its inner side a spring-receiving seat of rectangular form in

40 cross section across the joint of said two parts, one of said parts having its inner side beveled inwardly to the inner edge of said seat, and a spring of rectangular form in cross section and of undulating form circumferentially interposed between said ring groove and within

45 said spring-receiving seat, said beveled edge being adapted to guide said spring to said seat as said parts are assembled in said groove.

Signed at Los Angeles, Los Angeles County, California, this 14th day of October, 1932.
